DESIGN FOR A DECORATIVE SCARF OR THE LIKE

Sally Goldenstein, Brooklyn, N. Y.

Application November 26, 1947, Serial No. 142,813

Term of patent 3½ years

(Cl. D3—12)

To all whom it may concern:

Be it known that I, Sally Goldenstein, a citizen of the United States and resident of Brooklyn, in the county of Kings and State of New York, have invented a new, original, and ornamental Design for a Decorative Scarf or the like, of which the following is a specification, reference being had to the accompanying drawings, forming part thereof and in which the single figure is a plan view of the scarf or the like, showing my design.

I claim:

The ornamental design for a decorative scarf or the like, substantially as shown.

SALLY GOLDENSTEIN.
